US00D826412S

(12) **United States Design Patent** (10) **Patent No.:** **US D826,412 S**
(45) **Date of Patent:** **** Aug. 21, 2018**

(54) **ELECTRODE**

(71) Applicant: **Halo Neuro, Inc.**, San Francisco, CA (US)

(72) Inventors: **Matty Martin**, San Francisco, CA (US); **Tal Bar-Or**, San Francisco, CA (US); **Colin Davis**, San Francisco, CA (US); **Victoria Hammett**, San Francisco, CA (US); **Daniel Chao**, San Francisco, CA (US); **Brett Wingeier**, San Francisco, CA (US); **David Kaufman**, San Francisco, CA (US)

(73) Assignee: **Halo Neuro, Inc.**, San Francisco, CA (US)

(**) Term: **15 Years**

(21) Appl. No.: **29/612,745**

(22) Filed: **Aug. 3, 2017**

Related U.S. Application Data

(63) Continuation of application No. 29/553,732, filed on Feb. 4, 2016, now Pat. No. Des. 797,297.

(57) **CLAIM**

The ornamental design for an electrode, as shown and described.

DESCRIPTION

FIG. 1 is an isometric view, from the bottom back side, of the electrode.

FIG. 2 is an isometric view, from the upper front side, of the electrode.

FIG. 3 is an elevation view of the back of the electrode.

FIG. 4 is a plan view of the bottom of the electrode.

FIG. 5 is a plan view of the front of the electrode.

FIG. 6 is an elevation view of the top of the electrode.

FIG. 7 is an elevation view of the left of the electrode; and, FIG. 8 is an elevation view of the right of the electrode.

1 Claim, 3 Drawing Sheets
